UNITED STATES PATENT OFFICE

150,169

DESIGN FOR A MATCH BOX HOLDER

Charles E. Stockton, Manteca, Calif.

Application June 7, 1946, Serial No. 130,498

Term of patent 3½ years

(Cl. D48—28)

To all whom it may concern:

Be it known that I, Charles E. Stockton, a citizen of the United States, residing at Manteca, in the county of San Joaquin and State of California, have invented a new, original, and ornamental Design for Match Box Holder, of which the following is a specification, reference being had to the accompanying drawing, forming a part thereof.

The figure on the drawing is a perspective view, looking at one side of a match box holder, showing my new design; the opposite side of the match box holder presenting the same appearance.

I claim:

The ornamental design for a match box holder, as shown and described.

CHARLES E. STOCKTON.
